SINGLE CYLINDER ENGINE CONSTRUCTION

Peter Altman and Richard T. Robinette, Detroit, Mich., assignors to Continental Motors Corporation, Detroit and Muskegon, Mich., a corporation of Virginia

Application September 8, 1953, Serial No. 378,877

9 Claims. (Cl. 123—195)

This invention relates to a single cylinder engine construction and more particularly to a compact construction in which the oil pump and electrical ignition circuit breaker for said engine are combined into a unit sub-assembly directly insertable into and removable from the engine housing in an extremely efficient and effective manner.

The simplicity of assembly and disassembly from the engine of such vital coacting engine components as the oil pump and the electrical ignition circuit breaker is the essence of the invention. Because these components often times require repair and/or replacement at a greater rate than other elements of an engine, the facility of their repair and/or replacement is important from the standpoints of cost and time. If these smaller components of the engine can be easily and simply removed from and reinserted into the engine housing, it is not necessary to transport the entire engine about for repair. The single cylinder engine embodying the invention is particularly designed for incorporation into its housing of a combination assembly of an oil pump and electrical ignition circuit breaker.

An object of this invention is to provide an engine housing adapted to removably receive and support engine components.

Another object is the provision of an engine housing into which engine components may be inserted as complete sub-assemblies ready to coact with other components of the engine.

A further object is the provision of a compact single cylinder engine containing an oil pump and electrical ignition circuit breaker sub-assembly directly removable from and reinsertable into the engine housing as a unit.

Other features of the construction will become more apparent as the description of the invention unfolds below. For a visual understanding of the invention, reference is made to the accompanying drawings in which like parts are referred to by like reference numerals throughout the several views illustrating a preferred embodiment of the invention, and in which

Fig. 1 is a front elevational view of the engine, partially in section, in which the inventive construction is embodied.

Fig. 2 is a plan view of the engine of Fig. 1.

Fig. 3 is a vertical sectional view of that portion of the engine embodying the inventive construction, substantially on the line 3—3 of Fig. 2.

As seen in Fig. 1, the single cylinder engine 10 is provided with an outer housing shell 12 and an oil pan 14 bolted to the bottom of housing 12. To the left in Fig. 1, the oil pump portion 16 of housing 12 is capped by a retainer 18 which is held to the housing by bolts 20.

It will be shown by the description below that, upon removal of bolts 20, the entire sub-assembly 22 (Fig. 3) consisting of oil pump 24 and ignition circuit breaker 26 can be taken as a unit directly from housing 12 and out of engagement with other coacting components of engine 10.

2

As shown in Fig. 3, a single shaft 28 drives oil pump 24 and ignition circuit breaker 26. The lower portion 30 of shaft 28 is rotatably mounted in the support body 32 which is fabricated as a unit casting. The upper portion 34 of shaft 28 is similarly mounted in support body 32. Intermediate the ends of shaft 28 is a driven gear 36 fixedly mounted thereon, and caused to rotate by a driving gear 38 mounted on a camshaft 40 which gets its drive from crankshaft gear 42 (Fig. 1).

Beginning in the area of the oil pan 14, it will be noted that sub-assembly 22 comprises an oil filter 44 mounted on the support body 32 and adapted to pass the fluid oil to a pump gear 46 rotatably affixed to the lower end portion 30 of shaft 28. An oil passageway 48 is provided in body 32 leading to an oil tube 50 which is introduced into body 32 at the side of the housing 12 by fitting 52 that is threaded therein. An opening 54 in body 32 is designed to receive and pass tube 50 with its complementary packing seal 56, so that tube 50 serves to connect passageway 48 with the housing port or channel 58. The propelled oil flows through portion 58 to the various elements of engine 10 that require it, by suitable tubes and passageways (not shown) therein provided. Positioned above the driven gear and integrally formed therewith is a support 60 for governor assembly 62.

The governor assembly 62 generally comprises a pair of diametrically opposed pivotable counterweights 64, adapted upon rotation to raise a sleeve 66 on shaft 28 and bear against knuckle lever 68, which is pivotally mounted on a tubular shaft 70 arranged in housing 12. Tubular shaft 70 is a control element in the operation of the carburetor 72 for engine 10, through a lever system generally designated by the numeral 74. An external counterbalance system 76 is affixed to the opposite end of shaft 70, for control of governor 62.

At the upper end 34 of shaft 28 is the ignition circuit breaker 26 of assembly 22. This portion comprises a breaker point cam 78 mounted on shaft portion 34, arranged to operate above a plate 80 concentrically positioned by bolts 84 to the support body flange 82 (Fig. 3), holding the same in fixed position at the top. The screw fitting 52 together with connector tube 50 further prevents the support body 32 from rotating when driven gear 36 is in mesh with camshaft gear 38.

The support body 32 for assembly 22 comprises the upper flange 82, a connecting web 84, and the lower body portion 86. It will be noted that the flange 82 and lower body portion 86 support the two ends of shaft 28, which is rotatably driven at an intermediate point. A seal packing 88 is positioned around body 32 in housing 12.

The effectiveness of this compact construction is demonstrated by the means and method of removing the assembly 22 from engine housing 12. The threaded fitting 52 is screwed out of the housing. The cap bolts 20 are also removed, freeing the assembly 22 for removal. The governor weights 64 should be turned so that they are at right angles to the direction of knuckle lever 68. Then the retainer cap 18 is grasped and drawn directly upward along the axis of the shaft, freeing driven gear 36 of camshaft gear 38 (Fig. 3). Support body web 84 will slide along the inner wall surface of housing 12 until the lower body portion 86 meets camshaft gear 38. At this point the governor assembly 62 is clear of the housing 12. Assembly 22 is then tilted toward the principal portion of engine 10 (toward the right in Fig. 2), freeing body 32 of camshaft gear 38, and is then twisted or rotated to swing oil filter 44 out of the way of camshaft gear 38, the entire assembly 22 then being lifted directly out of housing 12. Knuckle lever 68 will swing about the axis of tubular shaft 70 against spring action of the counterbalance 76, and will

not prevent removal of the assembly 22, being substantially off-center with respect thereto.

For insertion of the assembly 22 into operating position in housing 12, the reverse order for removal is observed. By this novel and unique construction, the entire manufacture and servicing of these engine components has been extremely simplified, and compactness of engine 10 has been achieved.

It will be apparent to those skilled in the art to which this invention pertains that various modifications and changes may be made without departing from the spirit of the invention or from the scope of the appended claims.

I claim:

1. In an internal combustion engine provided with a crankcase and a rotating engine element supported by said crankcase, an engine cylinder carried by the crankcase, said crankcase having an opening therein downwardly into the crankcase interior, a unitary accessory assembly for said engine comprising a supporting structure having a cap portion fitted into said opening and serving as a closure therefor and provided with spaced upper and lower bearing supports, a shaft rotatably supported by said bearing supports and projecting above the top face of said cap portion, an ignition circuit breaker assembly carried by the projecting shaft portion, a cover for said ignition circuit breaker assembly and attached to the aforesaid cap portion, and a governor mechanism mounted on said shaft intermediate said upper and lower bearing supports, and a drive pinion on said shaft drivingly connected with said rotating engine element and located intermediate of said bearing supports.

2. In an internal combustion engine provided with a crankcase and a rotating engine element supported by said crankcase, an engine cylinder carried by the crankcase, said crankcase having an opening therein downwardly into the crankcase interior, a unitary accessory assembly for said engine comprising a supporting structure having a cap portion fitted into said opening and serving as a closure therefor and provided with spaced upper and lower bearing supports, a shaft rotatably supported by said bearing supports and projecting above the top face of said cap portion, an ignition circuit breaker assembly carried by the projecting shaft portion, a cover for said ignition circuit breaker assembly and attached to the aforesaid cap portion, and a governor mechanism mounted on said shaft intermediate said upper and lower bearing supports, and a drive pinion on said shaft drivingly connected with said rotating engine element and located intermediate of said bearing supports, said pinion comprising a common drive for said governor and said ignition circuit breaker and disposed immediately below said governor and above said lower bearing support.

3. In an internal combustion engine provided with a crankcase and a rotating engine element supported by said crankcase, an engine cylinder carried by the crankcase, said crankcase having an opening therein downwardly into the crankcase interior, a unitary accessory assembly for said engine comprising a supporting structure having a cap portion fitted into said opening and serving as a closure therefor and provided with spaced upper and lower bearing supports, a shaft rotatably supported by said bearing supports and projecting above the top face of said cap portion, an ignition circuit breaker assembly carried by the projecting shaft portion, a cover for said ignition circuit breaker assembly and attached to the aforesaid cap portion, and a governor mechanism mounted on said shaft intermediate said upper and lower bearing supports, and a drive pinion on said shaft drivingly connected with said rotating engine element and located intermediate of said bearing supports, said pinion comprising a common drive for said governor and said ignition circuit breaker and disposed immediately below said governor and above said lower bearing support.

support, said accessory assembly constructed and arranged for assembly through the aforesaid crankcase opening and extended into the crankcase interior between the rotating engine element and a wall of the crankcase.

5. In an internal combustion engine provided with a crankcase and a rotating engine element supported by said crankcase, an engine cylinder carried by the crankcase, said crankcase having an opening therein downwardly into the crankcase interior, a unitary accessory assembly for said engine comprising a supporting structure having a cap portion fitted into said opening and serving as a closure therefor and provided with spaced upper and lower bearing supports, a shaft rotatably supported by said bearing supports and projecting above the top face of said cap portion, an ignition circuit breaker assembly carried by the projecting shaft portion, a cover for said ignition circuit breaker assembly and attached to the aforesaid cap portion, and a governor mechanism mounted on said shaft intermediate said upper and lower bearing supports, and a drive pinion on said shaft drivingly connected with said rotating engine element and located intermediate of said bearing supports, said pinion comprising a common drive for said governor and said ignition circuit breaker and disposed immediately below said governor and above said lower bearing support, said accessory assembly constructed and arranged for assembly through the aforesaid crankcase opening and extended into the crankcase interior between the rotating engine element and a wall of the crankcase, said lower bearing support providing an oil pump recess at its lower extremity, an oil pump assembly mounted in said recess and drivingly connected with said shaft.

30 6. In an internal combustion engine provided with a crankcase and a rotating engine element supported by said crankcase, an engine cylinder carried by the crankcase, said crankcase having an opening therein downwardly into the crankcase interior, a unitary accessory assembly for said engine comprising a supporting structure having a cap portion fitted into said opening and serving as a closure therefor and provided with spaced upper and lower bearing supports, a shaft rotatably supported by said bearing supports and projecting above the top face of said cap portion, an ignition circuit breaker assembly carried by the projecting shaft portion, a cover for said ignition circuit breaker assembly and attached to the aforesaid cap portion, and a governor mechanism mounted on said shaft intermediate said upper and lower bearing supports, and a drive pinion on said shaft drivingly connected with said rotating engine element and located intermediate of said bearing supports, said pinion comprising a common drive for said governor and said ignition circuit breaker and disposed immediately below said governor and above said lower bearing support, said accessory assembly supporting structure having a reduced diametric cross-sectional dimension below said cap portion permitting said assembly to be tilted during assembly whereby to facilitate the passage of the lower bearing support and pinion in the limited space between the engine rotating element and the crankcase wall and at the final assembly allowing for 35 positioning of said shaft and bearing supports in axial alignment with said crankcase opening and to engage said pinion with said rotating engine element.

40 7. In an internal combustion engine provided with a crankcase and a rotating engine element supported by said crankcase, an engine cylinder carried by the crankcase, said crankcase having an opening therein downwardly into the crankcase interior, a unitary accessory assembly for said engine comprising a supporting structure having a cap portion fitted into said opening and serving as a closure therefor and provided with spaced upper and lower bearing supports, a shaft rotatably supported by said bearing supports and projecting above the top face of said cap portion, an ignition circuit breaker assembly carried by the projecting shaft portion, a cover for said ignition circuit breaker assembly and attached to the aforesaid cap portion.

75

portion, and a governor mechanism mounted on said shaft intermediate said upper and lower bearing supports, and a drive pinion on said shaft drivingly connected with said rotating engine element and located intermediate of said bearing supports, said pinion comprising a common drive for said governor and said ignition circuit breaker and disposed immediately below said governor and above said lower bearing support, said accessory assembly supporting structure having a reduced diametric cross-sectional dimension below said cap portion permitting said assembly to be tilted during assembly whereby to facilitate the passage of the lower bearing support and pinion in the limited space between the engine rotating element and the crankcase wall and at the final assembly allowing for positioning of said shaft and bearing supports in axial alignment with said crankcase opening and to engage said pinion with said rotating engine element, said supporting structure provided with an intermediate back structure integral with and connecting said upper and lower bearing supports, said back structure fitted snugly against the inside face of the crankcase wall at final assembly, said supporting structure provided with a drilled oil passage connected with the oil pump outlet and opening into the outer face of said intermediate back structure, said crankcase having an oil passage registering with the aforesaid drilled oil passage outlet in said supporting structure.

7. In an internal combustion engine provided with a crankcase and a rotating engine element supported by said crankcase, an engine cylinder carried by the crankcase, said crankcase having an opening therein downwardly into the crankcase interior, a unitary accessory assembly for said engine comprising a supporting structure having a cap portion fitted into said opening and serving as a closure therefor and provided with spaced upper and lower bearing supports, a shaft rotatably supported by said bearing supports and projecting above the top face of said cap portion, an ignition circuit breaker assembly carried by the projecting shaft portion, a cover for said ignition circuit breaker assembly and attached to the aforesaid cap portion, and a governor mechanism mounted on said shaft intermediate said upper and lower bearing supports, and a drive pinion on said shaft drivingly connected with said rotating engine element and located intermediate of said bearing supports, said pinion comprising a common drive for said governor and said ignition circuit breaker and disposed immediately below said governor and above said lower bearing support, said accessory assembly constructed and arranged for assembly through the aforesaid crankcase opening and extended into the crankcase interior between the rotating engine element and a wall of the crankcase, said lower bearing support providing an oil pump recess at its lower extremity, an oil pump assembly mounted in said recess and drivingly connected with said shaft, said accessory assembly supporting structure having a reduced diametric cross-sectional dimension below said cap portion permitting said assembly to be tilted during assembly whereby to facilitate the passage of the lower bearing support and pinion in the limited

space between the engine rotating element and the crankcase wall and at the final assembly allowing for positioning of said shaft and bearing supports in axial alignment with said crankcase opening and to engage said pinion with said rotating engine element, said supporting structure provided with an intermediate back structure integral with and connecting said upper and lower bearing supports, said back structure fitted snugly against the inside face of the crankcase wall at final assembly, said supporting structure provided with a drilled oil passage connected with the oil pump outlet and opening into the outer face of said intermediate back structure, said crankcase having an oil passage registering with the aforesaid drilled oil passage outlet in said supporting structure.

8. In combination an engine having a crankcase structure having an opening, a cam shaft rotatably supported thereby, a unitary accessory structure comprising an ignition circuit breaker and governor assembly, a one-piece frame structure having bearings and a common drive shaft supported by said bearings and carrying said governor and the rotor of said circuit breaker, a drive gear secured to said drive shaft and driven from said camshaft, said frame structure having an end plate carrying one of said bearings and providing a closure for the opening in said crankcase structure and locating said frame structure on assembly thereof with the engine crankcase, said frame structure fitted into said crankcase opening and disposing said governor and drive gear interiorly of said crankcase, said ignition circuit breaker assembly carried in its entirety by said frame structure whereby to adapt said unitary accessory structure assembly for insertion into and removal from said crankcase opening.

9. In combination, an engine, a housing for said engine having an opening therein and a fluid passageway therethrough, a unitary oil pump and ignition circuit breaker assembly for said engine adapted to be inserted into and removed from said engine housing as a unit through said engine opening, a second opening in said engine housing transverse to said first opening, and plug type tube means adapted to fit into and plug said second opening and to provide a fluid connection between said unitary assembly and said engine housing fluid passageway when said unitary assembly is positioned in said engine housing.
